STEREOTYPE-PLATE-COOLING APPARATUS

Application filed March 5, 1927. Serial No. 173,159.

This invention relates to the cooling of cast stereotype printing plates after they are cast.

The principal object of the invention is to utilize the period during which the plates travel from the casting room to the press room, or their equivalents, for cooling the plates and to provide practical and simple mechanism for that purpose.

Other objects and advantages of the invention will appear hereinafter.

Reference is to be had to the accompanying drawings in which

Fig. 1 is a side view partly in section of one embodiment of this invention;

Fig. 2 is a similar view showing another way of cooling the plate in accordance with this invention;

Fig. 3 is a similar view of a form of the invention in which the plates are immersed by a separate means;

Fig. 4 is a similar view of a fourth construction for this purpose; and

Fig. 5 is an end view of the mechanism shown in Fig. 4.

When a newly cast plate is delivered from the casting machine, it is too hot to be handled by the operator unless some form of cooling is provided. Several methods of cooling have been devised for this purpose, but the present invention relates to the cooling of the plate while it travels from the casting room to the press room, so that no time really is lost by the cooling process, the cooling all taking effect while the plate is travelling from one position to the other, where it has to travel anyway.

One of the simplest forms of cooling is shown in Fig. 1. In this figure the plate P is taken up by an endless chain conveyor 10 passing around sprocket wheels 11 and driven by a motor 12. This conveyor is provided with lugs 13 at intervals which, upon coming around into contact with the plate located over the conveyor, will engage the rear edge and move the plate along a pair of angle iron guides or tracks 14. These guides or tracks 14 extend from a point adjacent the casting apparatus in the casting room and the plates are delivered from the

casting apparatus directly to the tracks. The conveyor chain extending into the casting room beneath the tracks adjacent the point where the plate is delivered to the track, the lugs 13 are then brought into position to push the plates along the tracks. It will be understood that a chain conveyor is used ordinarily for taking the plates from the casting room to the press room or at least from one place to another. This conveyor also takes up the plate as shown at the left in Fig. 1 in the casting room, the plate being delivered to it, preferably by the casting machine, in position to be engaged by the lugs 13. The plate slides along with its edges on the two tracks 14 to a position indicated at the right where it enters the press room and is taken off the conveyor by hand and utilized in the ordinary way. The conveyor is endless, passing back to the starting position in the usual way.

For the purpose of utilizing the time required for taking the plate from the position shown at the left in Fig. 1 to that shown at the right, I employ a tank 15 filled with water, preferably. Instead of having the tracks 14 straight from one position to the other, I deflect the tracks down into the tank so that the plate is forced to travel down through the water for cooling it and up again to the proper level for delivery. The chains of course pass through the same curved path. In this way the plates are cooled while they travel from the casting room to the press room and no time is wasted in special cooling.

It is not necessary to immerse the plates in water and in Fig. 2 I have shown a modification of the form shown in Fig. 1 in which the same conveyor and tracks are used except that they are not deflected from the horizontal path. Instead of going through a tank and being immersed the plates are passed over a saddle 20 which is supplied with cooling water through a pipe 21. The saddle is provided with perforations 22 through which the water is discharged on the surface of the saddle to come into contact with the inside of the plate. The saddle is provided with grooves 23 for receiving it and draining it off so as to cool the plate on the interior. In

this case the plate passes along a straight path, preferably. The saddle may be of any desired length to secure the necessary cooling between one end of the conveyor and the other.

5 Another form of the invention is shown in Fig. 3. In this case the plate is taken along a straight track 24 formed of angle irons or the like, by a chain conveyor 25 which has only a 10 short travel. The conveyor takes the plate from the point at which it is deposited by the casting machine and, by means of its lugs 13, moves it on a cradle 26 as indicated in the drawing. This cradle at this time is located 15 at the level of the tracks 24 and in line with them. The plate is simply pushed on it by the action of the conveyor.

This cradle is pivotally hung from one pair of arms of a reel 27 which is mounted on a 20 shaft 28. On the shaft is a worm wheel 29 operated by a worm 30 on the shaft of a motor 31.

The electrical connections are not shown in full but when the plate is moved into the 25 position shown on the cradle 26 at the left; the lug 13, coming around underneath the end of the conveyor, closes a contact 32. This contact is located in the motor circuit and closes that so as to start the motor. It will 30 be seen that the conveyor 25 travels continuously through its motor 12. Now the reel composed of the arms 27 starts to rotate in the direction indicated by the arrow and moves 35 around until the plate just deposited in the cradle reaches the position at the bottom. This reel is located over a tank 15 such as shown in Fig. 1 and the rotation of the reel immerses the plate. At this point a lug 33 on another arm of the reel comes into contact 40 with a limit switch 34 which breaks the circuit and stops the motor and therefore the reel in that position.

By this time another plate comes along the conveyor 25 and is moved on to the next 45 cradle 26 and the contact 32 is again closed which starts the motor and the reel again. The reel rotates through a third of a revolution in the form shown and then stops and the plate we have been describing comes up 50 to the position indicated at the right hand side of the figure, where it hangs horizontally as shown. Now when the reel starts the next time, an arm 35 on the cradle comes into contact with a fixed stop 36 and during the first 55 part of this third of a rotation the cradle is tilted to the dotted line position. The plate then slides down the cradle by gravity on a series of rolls 37 which are arranged in inclined position and finally on a track 38 60 which is like the track 24. The two lower edges of the plate rest on the two angle irons, forming the track. Here the plate is picked up by another conveyor 39 and carried therefrom to the press room.

65 It will be seen that the revolving motion

of the wheel is intermittent and is started and stopped automatically by the action of the in-coming plate and the reel itself through the two switches 32 and 34. In this way all the plates are cooled the same length of 70 time and come into the press room in substantially uniform condition and ready for the press.

The same invention can be carried out in other ways, one of which I have illustrated 75 in Figs. 4 and 5. In this case the plate P is brought down an incline by the action of a conveyor 40. It is deposited on an inclined platform 41 mounted on the top of a stationary disc 42, which disc also is inclined 80 to give the platform its proper inclination so that the plate will slide down it by the action of gravity. This disc 42 has an opening 43 large enough to allow the plate to pass through it, this opening being slightly off 85 center. The end of the plate enters the opening and comes up behind the wall of a drum 44. This drum is mounted on a shaft 45 arranged at right angles to the plane of the disc 42 and therefore on an inclination. It is operated continuously by a motor 46 through worm gearing 47. This drum is provided with openings 48, shown as four in number. They are at the same distance from the center of the shaft 45 as the opening 43 and have 95 the same shape.

When the drum comes around in its rotation so that an opening 48 registers with the opening 43, the plate will slide down into this opening 48 and come up against a disc 100 49 which is like the disc 42. It is located parallel with it and is provided with one opening 50 which is centrally aligned and therefore out of alignment with the opening 43. Therefore the plate when it comes down 105 through the opening 48 engages the disc 49 and cannot pass out through the opening 50, but is forced to rotate around the drum 44. Then it passes into a tank 51 and as the parts do not fit closely, it immerses the plate 110 in water in the tank for a definite period of time and then brings the plate up. When it reaches the top, the plate will eventually register with the opening 50 and pass out through the same on an inclined shelf 52 115 down on an inclined series of rollers 53 to a conveyor 54 to be delivered wherever desired. The openings 43 and 50 are larger than the plate to allow the drum to move through a part of a revolution without rubbing the plate against the edges of these openings. The drum of course rotates slowly.

In all forms of the invention shown, the same advantages are secured as expressed above, and the amount of cooling is uniform 125 for the different plates so that they all reach the press room in the same condition of coolness and ready for use.

Although I have illustrated and described only four forms of the invention I am aware 130

of the fact that other modifications can be made therein by any person skilled in the art without departing from the scope of the invention as expressed in the claims.

5 Therefore, I do not wish to be limited to all the details of construction herein shown and described, but what I do claim is:—

10 1. In a device of the character described, the combination with a conveyor and tracks for supporting the straight edges of stereotype printing plates, the conveyor being arranged to move the plates along the tracks, of means located adjacent to the tracks for subjecting the plates to the action of a cooling medium as they pass along under the influence of the conveyor.

15 2. In a plate cooling machine, the combination with two conveyors separated from each other, the first conveyor being adapted to take a plate from the casting room and move it along a certain distance, a plate immersing mechanism in position to receive a plate from the first conveyor and move it down into a tank of water to cool it and up again to deliver it, the second conveyor being located at the other end of the machine in position to receive the plate from the immersing device and deliver it.

20 3. In a plate cooling machine, the combination with a feeding conveyor and a delivery conveyor for the plates, of a rotary member located between them and adapted to receive the plates, a cooling tank below said member into which the plates are passed by its rotation and out of which they are moved by the rotary member on the opposite side of said tank into position to be deposited on the delivery conveyor.

25 4. In a plate cooling machine, the combination with a reel, of a series of cradles pivotally mounted on the arms of the reel and hanging down in a horizontal position to receive a plate, means for rotating the reel intermittently so as to immerse a plate located on one of the cradles in a tank of water below and to move another cradle into receiving position and then stop, and means for automatically starting and stopping the reel in proper position for receiving and delivering the plates.

30 5. In a plate cooling device, the combination with a tank having cooling water therein, of a reel located over the tank and having arms projecting therefrom and cradles connected with said arms, of a motor for rotating the reel having electrical connections by which, when the reel rotates to a position in which one cradle is in position to receive a plate, the motor and reel will be stopped and, when the reel is started, it will be turned to bring that plate down into the tank for cooling it.

35 6. In a plate cooling device, the combination with a tank having cooling water therein, of a reel located over the tank, a motor

for rotating the reel having circuits for controlling it, said reel having a series of pivotally depending cradles for receiving and holding the plates to be cooled, the reel having means for stopping the motor when one of said cradles reaches receiving position, means for delivering a plate to a cradle in receiving position, and means on the delivering means for starting the motor when the plate is so delivered, whereby the plate will be lowered down into the tank to cool it.

40 7. In a plate cooling device, the combination with a cooling tank, of a reel located above it and having a series of cradles for receiving the plates, means for delivering a plate to a cradle in receiving position, said means having means for starting the motor when the plate is so delivered, whereby the reel will rotate and immerse the plate in the tank, means on the reel for stopping the motor when another cradle on the reel reaches the position to receive a plate, and means whereby when each cradle reaches delivery position it will be inclined to deliver the plate out of the cradle by gravity.

45 8. In a plate cooling device, the combination with a cooling tank, of a reel located above it and having a series of cradles for receiving the plates, means for delivering a plate to a cradle in receiving position, whereby the reel will rotate and immerse the plate in the tank, and means whereby when each cradle reaches delivery position it will be inclined to deliver the plate out of the cradle by gravity.

50 In testimony whereof I have hereunto affixed my signature.

OSCAR CHARLES ROESEN.
